CASE FOR SPECTACLES OR THE LIKE

Charles A. Baratelli, Southbridge, Mass., assignor
to American Optical Company, Southbridge,
Mass., a voluntary association of Massachusetts

Application November 5, 1952, Serial No. 22,142

Term of patent 14 years

(CL. D57—1)

To all whom it may concern:

Be it known that I, Charles A. Baratelli, citizen of the United States of America, residing at Southbridge, in the county of Worcester and State of Massachusetts, have invented a new, original and ornamental Design for a Case for Spectacles or the like, of which the following is a specification, reference being made to the accompanying drawings forming a part thereof.

Fig. 1 is a front elevational view of a case for spectacles or the like, showing my new design;

Fig. 2 is a rear elevational view of the case;

Fig. 3 is an end elevational view of the case; and

Fig. 4 is a perspective view of the case with the closure flap open.

My design for a case for spectacles or the like is characterized by a pocket portion having a flap portion which effectively rises out of the interior thereof along the inner surface of one wall and then extends over the open end of

the pocket portion onto the outer surface of the opposite wall of the pocket portion to lie exteriorly thereof when in closed position, as shown in full lines in the drawing.

I claim:

The ornamental design for a case for spectacles or the like, substantially as shown and described.
